UNITED STATES PATENT OFFICE

147,748

DESIGN FOR A SINK

Anna Harder, Beaver Dam, Wis.

Application December 28, 1945, Serial No. 125,069

Term of patent 14 years

(Cl. D4—2)

To all whom it may concern:

Be it known that I, Anna Harder, citizen of the United States, residing at Beaver Dam, in the county of Dodge and State of Wisconsin, have invented a new, original, and ornamental Design for Sink, of which the following is a specification, reference being had to the accompanying drawings, forming a part thereof.

In the drawing:

Figure 1 is a perspective view of the sink showing my new design.

Figure 2 is a top side plan view of the sink; and

Figure 3 is a cross sectional view taken substantially along the line 3—3 of Figure 2, looking in the direction of the arrows.

The dominant feature of my design resides in the specific configuration of the partition between the sink basin compartments, as shown.

I claim:

The ornamental design for a sink, shown and described.

ANNA HARDER.
